Primary Examiner — Bridget L Eland*(74) Attorney, Agent, or Firm* — Maier & Maier, PLLC**(57) CLAIM**

The ornamental design for a mobile phone, as shown and described.

DESCRIPTION

FIG. 1 is a front elevation view of a mobile phone, showing my new design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines in the drawings are for the purpose of illustrating portions of the mobile phone that form no part of the claimed design.
